Emery Vanney Blair & Hagnell

UNITED STATES PATENT OFFICE.

ALPHONSO V. BARTO, OF BRONXVILLE, NEW YORK.

CARRIER.

Application filed July 3, 1920. Serial No. 393,795.

To all whom it may concern:

Be it known that I, ALPHONSO V. BARTO, a citizen of the United States, and a resident of Bronxville, in the county of Westchester and State of New York, have invented an Improvement in Carriers, of which the following is a specification.

This invention has to do with a carrier and more particularly it relates to a hand carrier for readily transporting infants and small children.

One of the objects of this invention is to provide a carrier which preferably is for use in carrying infants in comfortable and safe positions and out of contact with the individual transporting the carrier, and to provide means for grasping the carrier so that it is readily held by one hand. Other objects of the invention will be apparent from the following detailed description.

A selected embodiment of this invention is illustrated in the accompanying drawings, wherein

Figure 1 is a perspective view of a carrier with its sides extended and with a prop shown in dotted lines; and

Figure 2 is a perspective view of the carrier with the sides folded over and held by a fastener.

Referring to the drawings, the selected embodiment is shown in the form of a carrier 1 having a back 2 and a seat or saddle 3 arranged to readily receive an infant on the seat or astride the saddle and against the back. Preferably the carrier is provided with sides 4 which are brought into contact with the infant and held in that position by any desirable means such, for instance, as strap 5 having a buckle 6. The carrier is provided with handles 7 which are readily grasped by one hand of an individual. Preferably, the handles cooperate with the sides to maintain the infant in a position so that it will not slide or roll from the carrier, but will be free to kick and move its arms about. However, either the sides 4 and the handles 7, or the sides 4 and strap 5, may be employed to maintain the infant in position on the carrier, and in the former case, if desired, the sides may be removed. A carrier of this type provides a means for easily transporting and holding infants in such a manner that they are safe from injury and cool and comfortable with their backs flat and

straight. The carrier is especially adapted for use in carrying the infant when traveling.

In constructing the illustrated carrier, the back 2 and the seat or saddle 3 are preferably formed by means of a suitable frame which has the saddle continuous with the back. Such a frame is readily provided by bending a wire 8 in any desired shape and is herein shown as oval shape. The frame, however, may be constructed of any desired material formed in suitable manner to support a child. After bending the wire to form the saddle and oval portions, it is preferably held flexed to increase the rigidity and is retained in that position by means of having its joining ends 9 and 10 held within a small pipe section 11 which prevents the ends of the wires from overlapping. The saddle portion 3 is held at an angle to the general plane of the oval portion by turning up the end of the frame as illustrated. However, the saddle may be formed at any desired point on the oval portion with a foot-rest or support below. For purposes of supporting the carrier on the ground or in other places and at an angle thereto, a supporting means such as a prop 12, shown in dotted lines on the drawing, may be provided. Preferably an attaching means such as eyelets 13 is formed by bending the wire 8 to receive the prop 12.

The supporting part of the carrier which receives the infant is preferably formed by stretching a flexible member, such as cloth, canvas, leather or other material over the frame and preferably it is formed continuous to enclose the part of the frame forming the saddle 3. The flexible member herein employed consists of one or more pieces of cloth sewn together so that the wire frame may be included between the pieces. The sides 4 are formed continuous with the main part and are of sufficient length to fold against the infant and hold it in position on the back 2, and the sides are held in position by fastening the strap 5 across the infant. There is included preferably between the frame and within the cloth a wadding 14 which forms a thin mattress. Preferably the sides 4 are not provided with wadding, but, if desired, it may be inserted therein. For purposes of sanitation, a sanitary apron may be fastened to the carrier, or the cloth

employed as the flexible member may be of sanitary structure.

Any suitable handle may be made and attached to the sides or frame and may be attached in a suitable manner, or the handle may be provided by extending the sides and forming apertures therein to create gripping edges. Preferably a single strip is employed to form the handles 7 and is attached to the 10 sides and passes underneath the carrier as shown in dotted lines. This strip may be made in two sections and attached only to the sides 4, or, if desired, may be attached to the frame proper. When the carrier is 15 supported by the handles they assist in maintaining the infant in the carrier in a flat or inclined position so that it cannot slip or roll therefrom and, in addition, they may be employed as a loop by which to hang the 20 carrier from a desired support. The lower portion of the strip which extends across the back 2 may be loose so that the prop 12 may be held between the strap and the back of the carrier to obviate the liability of the prop 25 engaging foreign objects while the carrier is being transported.

During or after the cutting and sewing of the flexible material into the shape which will enclose the wire 8, the wadding may be 30 placed therein and distributed evenly. The frame, after being bent, is then inserted between the pieces of the enveloping cloth and extended and fastened by having both ends 9 and 10 inserted in the pipe section 11. A 35 suitable means may be employed to retain the wadding in the seat or saddle in a position so that the frame does not bear directly against the infant, and preferably a large amount of wadding is stuffed in the saddle 40 portion to accomplish this purpose. If desired, an adjustable, sun-protecting covering may be attached to the carrier so that the baby's face may be correctly protected. Such a cover preferably comprises a stand- 45 ard having a clip on one end to contact with the frame and the adjustable protector on the other end to be held at a distance above the surface of the carrier.

This invention may be variously embodied 50 and the particular form of apparatus shown is capable of being varied within the scope of the subjoined claims.

I claim:

1. A carrier adapted to support children 55 comprising a flexible means held in extended position, a small area of said means being held at an angle to the remaining area of said means to form a saddle which functions to prevent a child from sliding from said 60 carrier, and a handle associated with said means for transporting said carrier.

2. A carrier adapted to support children comprising a frame held under flexure and having an end bent to form a saddle, a flexible means stretched over said frame, and a 65

means associated with said flexible means to maintain a child on said carrier and to transport the same.

3. A carrier adapted to support children comprising a frame having one end held 70 substantially at right angles to the rest of the frame to form a saddle, a flexible means enclosing said frame and having extensions for holding a child on said carrier, and handles associated with said extensions for 75 transporting said carrier.

4. A carrier adapted to support children comprising a frame having an upturned end, flexible means stretched across said frame and adapted to assist in holding a child, 80 flexible sides associated with said frame, and fastening means cooperating with said sides to hold the child in position on said carrier.

5. A carrier adapted to support children comprising a frame having one end held 85 substantially at right angles to the rest of the frame to form a saddle, flexible means enclosing said frame and having extensions, means for holding said extensions together to retain the child on said carrier, and handles associated with said flexible means for 90 transporting said carrier and when under tension to assist in maintaining the child in normal position.

6. A carrier adapted to support children 95 comprising an oval-shaped frame having a portion held at an angle thereto, a flexible means enclosing said frame and having a wadding within said flexible means, sides extending from the edges of said frame to 100 fold into contact with a child on the carrier, and handles associated with said sides and capable of being grasped by one hand for transporting the carrier.

7. A carrier adapted to support children comprising a frame having a portion thereof bent to form a saddle, a flexible means enclosing said frame and having wadding therein, said flexible means extended to 105 form sides to be folded against a child, fastening means associated with said sides 110 to hold the same in normal position, and a prop attached to said frame to hold the carrier in an upright or angular position.

8. A carrier adapted to support children comprising a frame having a portion thereof at an angle to a plane passing through the edges of the frame and having the frame bent to form eyelets in said plane, supporting means stretched over said frame for supporting a child thereon, sides for retaining the child in position, handles for transporting said carrier, and a prop engaging said eyelets to hold said carrier at an angle 115 when placed on a support.

9. A carrier adapted to support children in an inclined position comprising a saddle of small area, a back rest of relatively large area extending from said saddle and ar- 120 125 130

ranged to support substantially the full length of a child's back, and means associated with said back rest for transporting said carrier and for assisting in maintaining the child on said carrier.

5 10. A hand carrier for transporting children and being adapted to support a child in an inclined position, said carrier having a portion for supporting substantially all 10 of a child's back and having another portion in the form of a saddle to prevent the child from sliding from said carrier, and being provided with handles which may be 15 grasped with one hand and which normally hold the carrier so that the child is in the desired inclined position.

11. A carrier for supporting a child comprising a flexible material, a frame for maintaining said material in predetermined 20 position, said carrier formed to have two parts of different areas, said parts being positioned at an angle to each other, one part adapted to support the child on its back and

the other part adapted to maintain the child on the first part, and handles for transporting said carrier.

12. A carrier adapted to support children comprising a wire oval-shaped frame having two eyes formed therein to hold a prop and having its lower end bent at an angle to 30 form a saddle, a cloth covering stretching over said frame to form a support between the sides thereof, wadding within said cloth covering, flexible sides being extensions of said covering for folding against a child 35 held on said carrier, a strap to be fastened to each of said sides to hold the child in position, and flexible handles associated with said sides and passing under said frame and cloth and having length to have them meet 40 above said child and to be grasped by one hand.

In testimony whereof, I have signed my name to this specification this 2nd day of July, 1920.

ALPHONSO V. BARTO.
